UNITED STATES PATENT OFFICE.

HENRY B. MYERS, OF MARSHFIELD, MISSOURI.

RAILROAD CATTLE-GUARD.

No. 857,093.

Specification of Letters Patent.

Patented June 18, 1907.

Application filed February 28, 1907. Serial No. 359,803.

To all whom it may concern:

Be it known that I, HENRY B. MYERS, a citizen of the United States, residing at Marshfield, in the county of Webster and State of Missouri, have invented certain new and useful Improvements in Railroad Cattle-Guards, of which the following is a specification.

My invention relates to improvements in railroad cattle guards.

10 The object of my invention is to provide a railroad cattle guard which is economical in its construction and which is efficient and durable.

15 The novel features of my invention are hereinafter fully described and claimed.

In the accompanying drawings illustrative of my invention—Figure 1 is a vertical cross section taken on the dotted line *a—b* of Fig. 3. Fig. 2 is a top view of the cattle guard. 20 Fig. 3 is a longitudinal vertical sectional view taken on the dotted line *c—d* of Fig. 2. Fig. 4 is a vertical sectional view of one of the cattle guard members and a portion of one of the ties, taken on the dotted line *e—f* of Fig. 25 Fig. 5 is a view similar to Fig. 4, taken, however, on the dotted line *g—h* of Fig. 3.

Similar numerals of reference denote similar parts.

1 and 2 denote respectively the rails and 30 ties. Mounted on the upper side of the ties 2, and preferably at both sides of each rail 1, are a plurality of horizontal parallel substantially **V** shaped metal plates 3, the upper edges of each of which are provided with serrations 4. The ends of each plate 3 are flattened so as to firmly support the plate. Intermediate and opposite portions of each plate have downwardly turned projections 5 adapted to rest upon the upper side of the tie, 35 and which furnish lateral supports to prevent side tipping of the plate. Each plate is provided in its bottom portion adjacent its ends and in its middle portion with longitudinal slots 6, in which are mounted securing devices, such as the ordinary spikes 7, which 40 are driven into the ties 2. By providing the longitudinal slots 6 the plates 3 may be adjusted transversely on the ties 2, to positions in which the spikes passing through the slots 45 will enter the ties, even where the ties are not disposed at regular distances apart.

The plates 3 are preferably of galvanized sheet steel.

My invention may be modified in different ways within the scope of the appended claims 55 without departing from its spirit.

Having thus described my invention, what I claim and desire to secure by Letters Patent is:—

1. A cattle guard, comprising a plurality 60 of substantially **V** shaped parallel metal plates, adapted to be secured transversely to the railroad ties, and having serrated upper edges, the ends of each of said plates being flattened and opposite intermediate portions 65 of each plate being downwardly turned, thus serving as lateral supports.

2. In a cattle guard, the combination with the railroad ties, of a plurality of parallel substantially **V** shaped plates mounted upon 70 said ties and having serrated upper edges, each of said plates being longitudinally adjustable on said ties.

3. A cattle guard member, comprising a substantially **V** shaped plate having flattened 75 ends and opposite intermediate portions being downwardly turned so as to furnish lateral supports for said plate.

4. A cattle guard member comprising a substantially **V** shaped plate having flattened 80 ends, the upper edges of the **V** shaped portion being serrated and the plate being adjustable lengthwise on the railroad ties.

5. In a railroad cattle guard, the combination with the railroad ties, of a plurality of 85 parallel, substantially **V** shaped plates having flattened ends and intermediate opposite portions downwardly turned to serve as lateral supports, the upper edges of the **V** shaped portion of each plate being serrated, 90 and each plate having a plurality of longitudinal slots, and securing devices extending through said slots and into said ties.

In testimony whereof I have signed my name to this specification in presence of two 95 subscribing witnesses.

HENRY B. MYERS.
